UNITED STATES PATENT OFFICE

KENNETH J. TOBIN AND CARL E. EKLIND, OF CHICAGO, ILLINOIS, ASSIGNOR TO CAMEL COMPANY, A CORPORATION OF ILLINOIS

LOCKING MEANS FOR CAR DOORS

Application filed April 9, 1928. Serial No. 268,463.

This invention relates to latching means for car doors and concerns itself primarily with a single swingable bar for simultaneous latching a pair of hinged doors to the top and bottom of the car.

At the present time, a rotatable bar with a gooseneck is used to latch doors of the type under consideration. Slide bolts are also used for such a purpose. It frequently happens that the doors get out of alignment, due to various causes, and that the upper or lower edges of the doors will not come to home position and will stick out one or more inches, with the result that it is impossible to readily latch the upper and lower edges of the doors by the aforementioned gooseneck rod or the sliding bolts.

This invention is designed to overcome such defects and, to this end, a swingable bar engages flaring keepers upon the upper and lower ends of the car, even tho the doors are not in closed position, and, as the bar is swung under the flaring keepers, the doors will be forced inwardly to a tight closing position.

Further, the doors of the type above set forth usually have overlapping frontal margins. Consequently, as the latching bar is swung under the flaring or wedge-shaped keepers, the doors are brought snugly together at such frontal margins.

A further characteristic of this invention resides in a latching means for latching the swingable bar which tends to swing and maintain the swingable bar in firm relation with its keepers, thuswise taking up any lost motion or play.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is an elevational view of the end of a car which is closed by a pair of swinging doors which are latched and secured in accordance with this invention.

Figure 2 is an enlarged broken sectional view taken upon the line 2—2 of Figure 1.

Figure 3 is an enlarged sectional view taken upon the line 3—3 of Figure 2, looking in the direction of the arrows.

Figure 4 is an enlarged sectional view taken upon the line 4—4 of Figure 2, looking in the direction indicated by the arrows.

Figure 5 is a fragmentary enlarged elevational view illustrating the latching means for the swingable locking bar.

Figure 6 is an enlarged broken sectional view taken upon the line 6—6 of Figure 1.

In the drawings there is shown the end of a railway car which is closed by a pair of swinging doors 1 and 1a, which are hinged at their margins as indicated at 2. The frontal margins 1b and 1c of these doors overlap as shown in Figure 6. These doors may be of any desired construction, as their particular construction is immaterial, except insofar as the same may cooperate with this invention.

According to this invention, a vertical latching bar 3 is pivoted intermediate its ends to the door 1, the frontal margin of which overlaps the door 1a. While the particular manner of pivoting the bar to the door is immaterial, as a matter of illustration, the bar 3 is shown as provided with a projecting lug 4, which is pivoted to a casting 5 secured to the door.

The central portion of the latching bar 3 is preferably in the form of an I-beam, as shown in Figure 6, while the terminals thereof are formed of castings 6 and 7 bolted or riveted thereto. It will be noted that the free ends of the castings 6 and 7 are restricted, for the purpose of passing under keepers 8 and 9, which are respectively secured to the bottom and top of the car.

It will be noted that these keepers have outwardly inclined or flared portions 8a and 9a respectively and that the same are provided with horizontally projecting lips 10, under which lips 11, on the castings 6 and 7, are adapted to engage, as shown in Figures 3 and 4, whereby the upper and lower parts of the car structure are tied to the latching bar 3 when the same is in its operative closed position. For example, if the upper and lower

parts of the car should spread, the lugs on the keepers 8 and 9 would engage the lugs on the latching bar, which would act as a tie rod therefor. If the upper and lower parts of the car should contract or move together, the ends of the latching bar would resist such movement and said latching bar would then act as a compression member.

In order to limit the swinging movement of the latching bar 3, suitable stop members 12 may be secured upon the door 1 to which the bar is pivoted, as shown in Figure 1.

When the latching bar 3 has been swung to its closed position, it is desirable that the same be latched and sealed in such position. For this reason, suitable latching means has been provided, and this latching means is designed to so cooperate with the latching bar as to tend to swing the same to closed position and maintain the same in such position. To this end, a suitable casting 13 is attached to the door 1a and a swingable latching element 14 is pivoted at one end to the casting 13. The free end of the latching element has an arcuate surface 15 which is struck from the pivotal axis 16 of the latching element, as shown more clearly in Figure 5. The latching element 14 has a depending lug 17 which is adapted to cooperate with a lug 18 on the web of the I-beam 3.

The lugs 17 and 18 are suitably slotted for receiving a sealing ribbon, whereby the latching element 14 may be sealed with respect to the swingable bar 3. It will be noted that the latching element 14 rests upon the top of the lug 18 when the latching element 14 is in horizontal position. However, when the latching element 14 is swung downwardly, it may not at first reach the horizontal position and may be at an angle to the horizontal, due to the fact that the swingable latching bar has not been brought to true vertical position. Due to its weight, the latching element 14 will tend to gravitate downwardly and thus tend to bring the latching bar 3 to its true vertical position and to bring the ends thereof more firmly under the keepers 8 and 9. In other words, the latching element 14 automatically tends to swing and maintain the latching bar 3 in tightly closed position, and this tendency will, of course, be present as long as the latching element 14 is above the true horizontal position and is not supported upon the lug 18.

From the foregoing, it will be apparent that a very simple latching mechanism has been provided for simultaneously latching a pair of swinging doors in which the swingable latching bar aforescribed is effective for forcing home either the upper or lower ends of the doors in case they should not be moved to such position when the doors are swung into their closed position and in which the latching bar 3 serves as a tie post.

It will be noted that the flaring or wedging

flanges 8a and 9a on the keepers are at a sufficient angle to allow the ends of the locking bars to swing thereunder, even if the upper and lower ends of the doors are not in closed position. The swingable locking bar 3, therefore, also serves as an instrumentality for forcing the doors into closed position in the event that they do not come together for some reason.

It will also be appreciated that the locking element 14 automatically tends to right the locking bar 3 and maintain the same from swinging movements and in tight relation with its keepers.

It will be further evident that the swingable locking bar 3 not only locks the doors to the upper and lower ends of the cars but that it also maintains the overlapping frontal margins of the doors in tight and close engagement and that this position of the parts is maintained by the gravity-acting locking element 14.

We are aware that many changes may be made and numerous details of construction may be varied through a wide range without departing from the principles of this invention, and we, therefore, do not purpose limiting the patent granted hereon otherwise than necessitated by the prior art.

We claim as our invention:

1. In a house car having a pair of cooperative swingable doors with overlapping frontal margins, a latching bar pivoted intermediate its ends to the overlapping door, a keeper above said doors having an outwardly flaring flange with an inwardly extending lip, and a keeper below said doors having an outwardly flaring flange with an inwardly directed lip, said latching bar having terminals with outwardly directed lips for engaging under the lips upon said keepers, whereby said latching bar serves as a post for tying the upper and lower parts of the car together.

2. In a house car, the combination with a pair of swingable doors having overlapping frontal margins, a keeper above said doors, a keeper below said doors, said keepers having outwardly inclined flanges with overhanging lips, a latching bar pivoted intermediate its ends to the overlapping door and having terminals adapted for engaging the inclined flanges of said keepers for simultaneously moving the upper and lower parts of said doors inwardly, said terminals having lugs engaging under said lips, whereby said latching bar serves as a post for said car.

3. In a house car, the combination with a pair of swingable doors having overlapping frontal margins, a keeper above said doors, a keeper below said doors, a latching bar pivoted intermediate its end to one door and swingable under said keepers, and a latching element pivoted to one door and having a beveled end for engaging said latching bar

and a rest upon said latching bar for limiting the downward swinging movement of said latching element.

5 In testimony whereof we have hereunto subscribed our names at Chicago, Cook County, Illinois.

KENNETH J. TOBIN.
CARL E. EKLIND.
